[57] CLAIM

The ornamental design for a boat hull, as shown and described.

DESCRIPTION

FIG. 1 is a bottom right perspective view of the boat hull;

FIG. 2 is a right side view taken from FIG. 1, the left side view being the same;

FIG. 3 is a bottom view taken from FIG. 1;

FIG. 4 is a front view taken from FIG. 1;

FIG. 5 is a rear view taken from FIG. 1; and,

FIG. 6 is a top view taken from FIG. 1 in which the area inside the outline is unadorned.

FIG. 1.

FIG. 2.

FIG. 3.

FIG. 4.

FIG. 5.
